HARNESS STOP MOTION

Hormidas Laplante, Cranston, R. I.

Application October 7, 1947, Serial No. 778,487

7 Claims. (Cl. 139—337)

1

This invention relates to improvements in harness stop motion.

Electrical stop motions have been heretofore proposed which are adapted to be operated by an abnormal condition in harness frame connections, such as by a break therein, or when a substantial slack in the connections is had. Such prior construction has been presented in the horizontal connection of the harness connectors. In these prior constructions, spaced electric contacts are positioned beneath the loom to be engaged and bridged by the dropping of a bottom wire harness connector thereon due to a failure in the harness connections. The contacts are part of an electric circuit of a usual stop motion of a loom. The bridging of the contacts closes the circuit to actuate the stop motion. One of the disadvantages of such stop motion devices is that lint will fall thereon and soon pack on the contacts to such an extent as to prevent proper engagement thereof and render the device inoperable. Another disadvantage is that the device is not readily accessible at such a location as well as restricting the space which the loom fixer may require to occupy when repairing some particular element of the loom. It frequently happens in such instances that the loom fixer will disarrange some portion of the device by unintentional contact therewith, which may remain unseen and render the device inoperable.

An object of this invention is the provision of a stop motion wherein the electric contacts may be positioned to be engaged by the vertical end wires of the harness connectors to close the electric circuit of the loom stop motion.

Another object of the invention is the provision for controlling the electric circuit of the loom stop motion device at a location readily acceptable.

Another object of this invention is the provision of means for controlling the electric circuit of the loom stop motion device so constructed as to be maintained relatively free of lint.

Another object of this invention is the provision of a stop motion device which can be manufactured at a comparatively low cost of production, and which will be durable and satisfactory in use.

With these and other objects in view, the invention consists of certain novel features of construction as will be more fully described and particularly pointed out in the appended claims.

In the accompanying drawings:

Figure 1 is a front elevation showing those parts of a loom only which are necessary to understand the invention, and with certain parts

5 of the loom stop motion shown diagrammatically;

Figure 2 is a perspective view of a fragmental portion of the side frame with contacts attached thereto which form part of one embodiment of the invention;

Figure 3 is a section taken substantially along line 3, 3 of Figure 1;

Figure 4 is a perspective view illustrating diagrammatically part of a loom warp stop motion device; and

Figure 5 is a perspective view of one of the electric contacts shown in Figure 2.

In carrying out one embodiment of my invention, I provide an electrical contact in the form of a wire loop through which the end wires of the harness connection extend. The sides of the loop are spaced from each other a distance sufficient to prevent engagement of the end wire therewith in the normal operation thereof. However, should an abnormal condition in the harness connection occur, such as by an undue slackening of the connection or a breakage therein, then the end wires will be displaced from their normally generally vertical position sufficient to engage the electric contact and close the electric circuit of a usual stop motion device provided on the loom.

In the usual stop motion provided on a loom, one branch of the electric circuit usually includes the loom structure, which places the end wire in the electric circuit through its connection with the harness jack of the shedding mechanism of the loom. Should this branch of the electric circuit be broken, such as by a break in the connection between the end wires and the harness jack, a second contact in electrical engagement with the loom is provided at a position to be engaged by the end wires, and thereby position the same in the electric circuit of the stop motion. By this arrangement the control of the electric circuit is assured regardless as to where the failure of the harness connection may take place.

Referring to the drawings for a more detailed description of the invention, 10 designates one of 45 a plurality of a conventional type harness frame for mounting the heddles 11 which support the warp in the process of weaving. The harness frame comprises upper and lower rails 12 and 13 which are secured to each other at their end portions by uprights 14. The harness frame is suspended in position by flexible straps 15 and 16 which are attached to the upper rail 12 by spaced hooks 17. These straps pass over guide sleeves 18, 18 which are usually fastened for free rotation to the arch of the loom (not shown) and

are attached by means of wire connectors 19 and 20 to the vertical arm of a lever 21. The lever 21 is pivotally mounted for rocking motion about a shaft 22 and is part of the shedding mechanism of the loom.

The lever 21 or so-called harness jack, has a lower substantially horizontal arm 23, and has a wire connector 24 attached thereto. This wire connector extends generally vertically adjacent the side 25 of the loom frame, and the lower end of the connector is hooked to a flexible strap 26. The strap 26 passes beneath guide sleeve 27 and extends horizontally, having connections with a wire connector 28. The connector 28 extends horizontally and is hooked at the other end thereof to a strap 29 which passes under a guide sleeve 30 and then upwardly, having connections with a yoke or bowed wire connector 31. This yoke depends from and is secured to the lower rail 13 by means of hook eyes 32. This completes the connection between a harness frame and a harness jack 21 of the warp shedding mechanism. When the harness jack 21 is rocked about the shaft 22, the harness frame 10 will be raised and lowered to form the shed. The loom is provided with a multiple of motion just described, there being a plurality of harness frames, each of which is provided with its own connection and harness jack. The connectors 24 are usually referred to as the end wires; while the connectors 28 are referred to as the bottom wires.

The loom is also provided with an electrically operated warp stop motion which is illustrated diagrammatically in Figures 1 and 4, and comprises generally of a rocking lever 33 which is pivotally mounted on a rod 34 and has a control rod 35 pivotally mounted to its lower end as at 35'. A so-called dagger 36 is pivotally mounted to the upper end of the lever 33 to be held in a raised or lowered position by an arm 37 and a connecting link 38. The arm 37 is operated to raise the dagger 36 by an electromagnet (not shown), contained in a housing 39. When the dagger 36 is raised by energizing the electromagnet, it is positioned in the path of movement of and engaged by a bunter on the lay or other moving part of the loom (not shown), to rock the lever 33. The rocking motion of the lever 33 is transmitted through the control rod 35 to actuate a loom mechanism (not shown), to stop and bring the loom to rest. Electrical current may be supplied to the electromagnet, such as by means of an electric circuit including line wires L, transformer T, a conductor 40 to the electromagnet, and a conductor 41 to some part of the loom structure, such as the side frame 25 to provide for a return branch to the transformer.

The harness straps and wire connectors form a closed loop and are maintained taut to positively control the movement and position of the harness frame as the harness jack is rocked. Should the harness connections become unduly slack or broken, the harness frame will drop or become misplaced, so that it cannot properly shift the warps to form the shed.

In order to provide for stopping the loom upon harness connection failure, as above stated, I mount an electrical contact generally designated 43 to the side 25 of the loom at a location intermediate the ends of the wire connector 24. The contact 43 is in the present embodiment of the invention made in the form of a wire loop 44, see Figure 5. This wire loop may be conveniently made by bending a length of wire intermediate the ends thereof in a manner to form a closed

loop 45 with one wire length 46 extending in one direction, and the other wire length 47 extending in an opposite direction substantially in line with the length 46. The wire length 46 is bent 5 into substantially U shape providing a bridging portion 48 and an arm 49 extending therefrom. The wire length 47 is also bent back upon itself in substantially U shape, but inwardly of the arm 49 providing a portion 50 extending inwardly of the arm 49 substantially parallel thereto and spaced therefrom with the free end thereof extending to and secured to the bridge portion 48. The free end portion of the arm 49 is bent inwardly so as to extend toward the portion 50 and has the end extremity thereof form into a hook portion 51 to detachably secure the arm 49 to the portion 50; thus providing a closed loop 52. The resiliency of the wire is such as to act in a direction to bias the hook into engagement with the portion 50.

This electrical contact is secured in position to the side 25 of the loom by means of a bolt or the like 53. The shank of the bolt passes through the loop 45 and an opening 54 in the side 25 with the head of the bolt abutting against the edges of the loop 45. A nut 55 engages the threaded portion of the bolt and clamps the contact 43 in position in a usual manner. This contact 43 is electrically insulated from the loom by an insulating bushing 56 encircling the shank of the bolt and by insulating washers 57, one of which is positioned between the side of the loom and the edges of the loop 45 and the other of which is positioned between the side of the loom and the nut 55. This contact 43 is placed in the electric circuit of the loom stop motion by means of an electrical conductor 58 extending from the bolt 53 to the electromagnet of the stop motion. The end wire 24 is electrically conducting and through 10 its connection with the harness jack 21 is in the other branch of the circuit and forms another electrical contact. The end wire 24 is positioned to extend through the loop 52 of the contact 43 and is normally out of contact therewith. The loop is made of a sufficient width so as to provide sufficient space to prevent accidental contacting of the end wire 24 by any vibration thereof when the loom is in motion. Should any of the harness connection become unduly slack or break, 15 the wire 24 will slacken and be displaced from its general vertical position to a slant sufficient to make contact with the side of the loop 52, thereby closing the electrical circuit to the electromagnet to actuate the warp stop motion in a manner 20 above described to bring the loom to rest.

Should the end wire 24 become detached from its connection at the harness jack, the electrical connection of the end wire would then be broken. In order to provide for such an emergency, a contact designated generally 58 is provided. This contact is also in a form of a wire loop 59, best shown in Figure 2 and is attached to the side 25, such as by means of a bolt 26, and is electrically connected thereto; thus forming an additional contact 58 engageable by the end wire 24 so as to provide an additional connection therefor to the electric circuit of the stop motion. This contact is positioned at a location spaced and beneath the contact 43 and the end wire 24 extends therethrough and makes engagement therewith upon harness connection failure.

When the loom is in motion, a certain amount of vibration sets in the contact 43. This vibration has been found sufficient to prevent lint from 25 accumulating to any material degree on the con-

tacts 43 and 58; thus assuring of a positive engagement between the end wires and the contacts.

I have shown and described my invention in connection with electrically operated stop motion which is usually provided on most looms; however, other electrically operated loom stopping means may be provided, if desired.

I claim:

1. In a loom, a harness frame, normally taut suspension means for operating said frame, including an electrical conducting connector, an electrically operated stop motion for said loom, an electric circuit for said stop motion, said connector being in the said circuit forming a first contact, a second contact in the said circuit spaced from the first contact and encircling said connector and engageable by said connector to close said electric circuit to said stop motion, when said suspension means become slack or broken. 10

2. In a loom, a harness frame, normally taut suspension means for operating said frame including a vertically extending electrical conducting connector, an electrically operated stop motion for said loom, an electric circuit for said stop motion, said connector being in the said circuit forming a first contact, a second contact in the said circuit spaced from the first contact and positioned adjacent the said connector and engageable by the vertically extending portion of said connector to close said electric circuit to said stop motion when said suspension means become slack or broken. 20

3. In a loom, a harness frame, normally taut suspension means for operating said frame including a vertically extending electrical conducting connector, an electrically operated stop motion for said loom, an electric circuit for said stop motion, said connector being in the said circuit forming a first contact, a second contact in the said circuit spaced from the first contact and secured to the side of the loom adjacent said con- 30

35

6

nector and engageable by said connector to close said electric circuit to said stop motion when said suspension means become slack or broken.

4. In a loom as set forth in claim 1, wherein said second contact is in the form of a wire loop. 5

5. In a loom as set forth in claim 1 wherein said contact is in the form of a wire loop attached to the side of the loom and electrically insulated therefrom.

6. In a loom as set forth in claim 1, wherein an additional contact is provided comprising a wire loop secured to the loom frame and in said circuit, and through which the said connector passes.

7. In a loom having a loom frame and a harness frame, normally taut suspension means for operating said harness frame including an electrical conducting connector having at least a portion thereof extending generally vertically, an electrically operated stop motion for said loom, an electric circuit for said stop motion, said connector forming a contact in the said circuit and contact means in the said circuit spaced from the said contact and attached to a side of the loom frame adjacent the said connector and engageable by said portion of the connector to close the electric circuit of the stop motion to stop the loom when said suspension means becomes broken. 25
